UNITED STATES PATENT OFFICE.

GEORGE C. CHASE, OF SOUTH ORANGE, NEW JERSEY, ASSIGNOR TO MONROE CALCULATING MACHINE COMPANY, OF ORANGE, NEW JERSEY, A CORPORATION OF DELAWARE.

MULTIPLIER MECHANISM FOR CALCULATING MACHINES.

Application filed March 15, 1926. Serial No. 94,968.

This invention relates to means for accomplishing multiplication in calculating machines, such, for instance as the reversible cycle calculator disclosed in Patent No. 5 1,566,650, issued to Geo. C. Chase, on Dec. 22, 1925, entitled Operating means for calculators, being shown as applied to a machine constructed in accordance with the reissue patent to Baldwin, No. 13,841, as modified 10 by the Patent No. 1,474,230, issued to E. F. Britten, Jr., Nov. 13, 1923, and by the above noted patent to Chase.

An object of the invention is to provide 15 multiplier key mechanism, whereby the depression of a key will determine the number of times that an amount set up on the multiplicand keys will be added upon the numeral wheels; in combination with means for terminating an operation upon an overrun of the 20 tens carrying mechanism.

A further object is to provide a bank of 25 multiplier keys with locking devices, whereby the depression of one key of the bank will lock the other keys until the partial product determined by the depressed key is registered.

Another object is to provide means whereby the locked keys are automatically released 30 and the depressed key restored to raised position when the registration determined by the depressed key has been completed; or, the registration having been completed, when the operator releases the depressed key.

The invention consists in the novel construction and combination of parts as set forth in the appended claims.

In the accompanying drawings illustrating the invention,—

means for actuating all of the clamping devices, together with equalizing devices in the power drive. Fig. 3 is a view similar to Fig. 2 but showing fluid actuated power means 5 for controlling the clamping devices. Fig. 4 is a side view of Fig. 3 certain parts being broken away better to illustrate the invention. Fig. 5 is an end view of Fig. 4, also with certain parts broken away. Fig. 6 is 10 a vertical section showing one form of manual means for actuating the clamping devices. Fig. 7 is a section on the line 7—7 of Fig. 6. Fig. 8 is a section on the line 8—8 of Fig. 6. Fig. 9 is a vertical section of another form of 15 manual means for actuating the clamping devices. Fig. 10 is a detail section on the line 10—10 of Fig. 9.

Referring more particularly to the drawings the invention is disclosed as associated 20 with a radial drill comprising a column C, radial-arm A and the usual drill-head D adjustably mounted on the arm. Within the drill-head is journaled a spindle S adapted to receive a drill-point or other suitable tool. 25 Power to translate the arm vertically on the column and to rotate the spindle may be provided by a motor M, or other prime-mover, preferably located at the foot of the column and such power may be controlled by suitable 30 mechanism which, being conventional, need not be described. Machine-tools of this type are usually provided with or mounted upon a base which in turn is secured to a suitable stationary foundation or floor. A base of 35 this nature is illustrated at B which, however, when used in connection with the present invention is not permanently secured in any definite position but which instead is adapted to be moved relative to its support. This 40 invention relates particularly to the means permitting transportation of the base and means for securing it either temporarily or permanently in any desired location. Obviously any type of machine-tool could be so 45 mounted, transported and secured in position, therefore it is to be understood that the invention is adaptable to various other machine-tools and is not limited to radial-drills.

To facilitate the transportation of the machine its base is preferably provided with suitable anti-friction devices such, as for example wheels or rollers 1. Preferably these anti-friction devices are guided to move in a predetermined path. This may conveniently 50 be accomplished by forming the wheels with side flanges and fitting them upon suitable tracks such as the rails 2. Adjacent the wheels 1 the base is provided with locking devices 3 which, when the base and the machine-tool thereon has been moved to any desired 55 location, may be actuated to secure the base to some immovable object such as, for example, the rails 2. These locking devices 60 preferably comprise vertically movable 65 clamping blocks 4 having jaws 5 and 6 adapt-

ed upon upward movement to engage the under-side of the head of the rail 2. Thus the rail-head is gripped between the lower surface of the wheels 2 and the jaws 5 and 6 and the machine base is held against movement both vertically and horizontally. 70

These blocks 4 are fitted within heavy brackets secured to the base B and are held against rotary movement therein in any suitable manner. As shown in Figs. 7, 8 and 9 75 this may be accomplished by forming the blocks with polygonal portions 4* and fitting them within similarly shaped sockets 7* in the brackets. Thus the blocks are held against rotation and the jaws 5 and 6 are 80 therefore prevented from binding upon the webs of the rails 2.

An important feature of this invention resides in the employment of the double gripping jaws 5 and 6 adapted simultaneously to 85 grip the rail head at opposite sides of the central web, thereby drawing the machine base firmly to the rails without creating any side strain on the clamping mechanism or on the rail. 90

As hereinbefore stated either manual means or power means may be utilized to actuate the clamps. Figs. 9 and 10 illustrate one simple and effective means for accomplishing this result manually. In this form the 95 blocks 4 are vertically movable in brackets 7 secured to the base B. Each of these blocks are provided with a threaded aperture 8 into which is threaded a screw 9 held against end-wise movement in the bracket 7 by collars 10 100 and 11. Upon the upper end of the screw is carried a hand-wheel 12 by means of which the screw may be manually rotated. To effect a final tightening of the clamp and to release it when it is desired to move the machine, 105 the wheel is preferably secured to the screw 9 by means of a lost motion connection which permits a partial rotation of the wheel relative to the screw whereby the wheel may be caused to strike a hammer blow on the screw 110 to give it a final or initial rotary movement. This may be effected by securing upon the upper end of the screw, as by fitting it to a squared end 13, a sector 14 affording radial walls 15 and 16. The hub 17 of the wheel 12 115 is formed with a cavity 18 larger than the sector and within which the latter is held. This cavity 18 terminates at one end in a stop-wall 19 adapted in one direction of rotation of the hand-wheel to engage the wall 15. 120 The opposite end of the cavity affords a wall 20 adapted to contact with the wall 16 when the hand-wheel is rotated in the opposite direction. Due to the lost motion between the wall 15 and 19, and 16 and 20 these walls 125 may be brought together forcibly to produce a final setting or an initial release of the clamp. A cover-plate 21 and a nut 22 serve to hold the parts in their assembled relation.

Another manual means for rotating the 130

spring to raise pawl 136, whereupon the contact of lug 141 with lug 142 will raise the forward end of lever 31 and trip stop element 25, to stop the machine at full-cycle position (see Fig. 22).

Arm 24 of the stop mechanism is provided at its upper end (shown as pivoted coaxially with element 25) with a laterally yieldable spring tooth 149, normally abutting against lug 148 of releasing pawl 136. Upon depression of pawl 136, consequent upon depression of the add, the subtract or a multiplier key, lug 148 will move downwardly past tooth 149 and spring 138, moving said pawl, will bring lug 148 beneath tooth 149 (see Fig. 21). Upon release of the key, pawl 136 will rise and its lug 148 will raise tooth 149 against the tension of its spring (see Fig. 22), in which position it will remain until arm 24 is carried forward, against stop 29 in the operation of the stopping means, when tooth 149 will be released and will resume a position in line with lug 148. In the rebound of the parts following contact of arm 24 with stop 29, the lug 30 of stop element 25 will pass below the forward end of lever 31, the latter being held in raised position by releasing pawl 136. Tooth 149 will now contact with lug 148 and move the releasing pawl to bring its lug 141 from beneath lug 142, whereupon the releasing pawl will be raised by the releasing lever spring to normal position, and lever 31 will fall and rest upon lug 30. Stop element 25 has thus been allowed to remain in contact with rock-lever 22, and link 21 moving through dead center position, the parts will be stopped a second time, should the rebound thereof be sufficient (see Fig. 25), following which stop element 25 will be restored to normal restrained position by contact of lug 30 thereof with the end of lever 31, as in Fig. 20.

Division is accomplished upon this machine preferably by the method of repeated subtraction and the determination of a quotient figure may be made automatic by means of a special stop control, as follows:

The divisor set up on the keyboard being subtracted, by holding down subtract key 121, one more than the number of times it is contained in the corresponding portion of the dividend registered in wheels 13, a negative numeral wheel reading is obtained, the higher order numeral wheels 13 passing to a registration of nine as far to the left as carry over mechanism is provided. The carry pin *q* (Fig. 19) of the numeral wheel which is in position to be acted upon by the extreme left-hand carry tooth *j* (Fig. 3) will lie in such relation to lever 31 as to operate a cam 32 of said lever as the wheel passes to 9, (Fig. 19) thereby raising the forward end of lever 31 and releasing stop element 25, to bring the machine to rest. In the machine illustrated, the stopping of the actuators will not be purely automatic, since if the operator

continues to hold down the subtract key, the machine will immediately resume the operation. The return of the reversing clutch lever 111 to neutral position, resulting from the tripping of element 25, will, however, through parts 128, and 125, communicate a slight upward movement to subtract key 121, this movement serving as a signal to the operator to remove finger pressure from the key. The wheel 85 which is being operated at the time will now register one more than the true quotient, and a corrective additive operation is performed, by depressing add key 120. This will cause the carry teeth to return the wheels 13 reading nine to a zero registration, and the pin *q* of the left hand wheel will again operate lever 31 and release the stop, whereupon the machine is brought to rest with the proper quotient figure upon wheel 85 and the proper remainder upon wheels 13. The use of the carriage 2 in continuing the division is well-known and needs no description.

Multiplier mechanism. Figs. 10-17.

According to the embodiment of the invention illustrated herein, the following multiplier devices are provided, which cooperate with the mechanism hereinbefore described to provide for the automatic determination of product figures.

A bail 250, pivoted to the framing at 251, 251, carries a slide 252 secured thereon by a pin and slot connection, the slide being held in rearward position by means of a spring 253. The lower ends of bail 250 are extended past the pivots 251 at 284 below the lower keyboard plate, and contact with a locking bail 254, also pivoted upon and depending from pivots 251, 251. An intermediately fulcrumed lever 255 engages a perforation 256 of bail 250, said lever forming in effect a depending extension of said bail. A spring 257 holds bail 250 and lever 255 normally in position with said bail engaging a stop 258 (Fig. 17). Slide 252 is provided with lateral spaced teeth 259, which in the normal position of the slide lie within notches 260 of the stems of the multiplier keys 261 (Fig. 14). The notch 260 of each multiplier key has an upper inclined edge 262, terminating at the lower edge of a shallow notch 263, the inner or stop wall of which is located in a plane of movement intersecting an intermediate point of said cam face. Upon depression of a multiplier key cam face 262 engaging the tooth 259 of slide 252, will rock bail 250 to the left until the tooth escapes from said edge, when the bail will assume an intermediate position, where it will be held by engagement of tooth 259 with the stop wall of notch 263 in which position the multiplier key will be in its fully depressed position, further depression of the key is prevented by engagement of a suitable stop, and return of the key to raised

- position by its spring is prevented by engagement of notch 263 with tooth 259 (Fig. 15). The free ends 284 of bail 250 abut against a flange 264 of locking bail 254, so that as bail 250 is rocked toward the left, the bail 254 will be rocked toward the right, where it will lie beneath the spring pawls 265, of the multiplier keys not depressed, whereby these keys will be locked in raised position.
- 5 This locking of the multiplier keys in raised position will prevent confusion of the registration by depression of a second key before completion of the registration determined by the first key. Such confusion might 10 occur, in the illustrated embodiment of the invention, from an attempt to correct a multiplier figure; and also in certain practical methods of operation, wherein the operator may have occasion to depress multiplier keys 15 in rapid succession, without any time lapse or intermediate operation of any kind. The confusion might occur in the registration of any successive multiplier figures, should the invention be applied to a machine equipped 20 with an automatic shift for the numeral wheel carriage.
- 25 Bail 250 and lever 255 having been rocked to extreme position by partial depression of the multiplier key, an inclined edge 266 of the lower arm of said lever will contact with the roller 267, mounted at the end of an arm 268 secured to rock shaft 125, and by depressing said roller will rock the shaft 125 in a 30 counterclockwise direction as viewed in Fig. 10. This movement, as previously explained, will start the machine in rotation in an additive direction while bail 250 is in its intermediate position, shaft 125, lever 128 and lever 134 will hold pawl 136 sufficiently depressed to avoid the tripping of trigger 31 (Figs. 20 and 26).
- 35 In order to stop the machine at the end of a number of cycles of operation determined by the multiplier key which has been depressed, the following mechanism is provided:
- 40 On slide 252 (Figs. 10-13) is mounted a pawl 269, which as bail 250 is rocked to the left will engage the rack teeth 270 formed in bar 271 slidably supported on the framing of the machine, and provided with a roller 272 engaged by the forked end of a lever 273 fulcrumed at 274 to the framing and bearing a 45 roller 275 engaged by a cam 276 mounted on shaft 4. The parts are held rearwardly against cam 276 by means of a spring 277.
- 50 Thus, at each rotation of shaft 4 slide 252 will be advanced a distance corresponding to one tooth of the rack 270 and will be held in progressively advanced position by means of a spring pawl 278, pivoted to the framing, and engaged by rack teeth 279 of slide 252 when bail 250 is swung to the left upon depression of a multiplier key. In extreme left 55 hand position of slide 252, pawls 269 and 278 yield slightly, and will remain in engagement with their rack teeth in the intermediate position of the bail and slide, when the tooth 259 of the latter enters the notch 263 of the key. 70 The teeth 259 on slide 252 which, as stated, lock down the multiplier keys, vary in breadth, the tooth cooperating with the 1 key being adapted to be moved out of register with the keys upon forward movement of 75 slide 252 one step; the tooth cooperating with the 2 key normally extending rearwardly of the key stem a sufficient distance to register therewith until slide 252 has been moved forwardly two steps, etc. progressively, until the tooth cooperating with the 9 key provides 80 for registration until the slide has been moved nine steps. In Fig. 13 the slide 252 is shown as having been advanced four steps by four rotations of the actuating means of the machine, and, since the 5 key is depressed, the next rotation of the actuating means will release the key. Upon release of the key, bail 250 with slide 252 returns to normal position, 85 releasing the pawls 269 and 278, and allowing slide 252 to return to its normal rearward position under the action of spring 253. The return of bail 250 to normal position also restores lever 255 to normal position, releasing roller 267 and shaft 125, whereby the actuating means will be stopped in the manner 90 previously described.
- 95 It has been stated that upon return of shaft 125 to normal position upon release of the add, subtract or a multiplier key, the machine 100 will continue in operation until the actuators reach full cycle position. Preferably, in the construction illustrated, cam 276 will advance slide 252 in the mid-cycle position of the numeral wheel actuating means, and for 105 this reason it is desirable to prevent the depression of a multiplier key during the interval between the release of the key previously depressed and the completion of the stopping action. For this purpose a spring latch 280 (Figs. 17 and 18) is provided to hold the locking bail 254 in engagement with the pawls 265 of the keys. In normal operation, finger pressure upon the multiplier key being removed before the release of the key from slide tooth 259, the multiplier key spring 285 will restore the key to raised position, the pawl 265 of said key yielding as it is moved past locking bail 254 and returning to normal position 110 above said bail, to lock the key against a second depression before the machine has been brought to rest. In effecting the stop, rock arm 24 is brought against stop 29 and the parts are allowed to rebound, as previously 115 stated, until the crank connections 20, 21 having passed through dead center position, arm 24 is again brought into contact with stop 29. During the first or additive contact with the stop the push rod 47 pivoted to arm 24 will 120 be held by pin 50 of link 21 out of contact 125
- 130

with a lever 283. During the rebound, the parts moving in a subtractive direction, pin 50 will hold the push rod 47 in position of contact with lever 283, so that the latter will 5 be actuated and a cam arm 281 thereof brought against latch 280 to move the same and release locking bail 254. The locking bail, being released, is returned to normal position by spring 282 and the multiplier keys 10 are free to be depressed.

It is desirable that any operative impulse imparted to a multiplier key should become effective (provided pressure is continued until the key yields under the finger), even 15 though an operator attempts to depress it while it is still locked by bail 254, the machine not having completed a previous multiplier operation. At this time pawl 265 acts like a rigid part of the multiplier key, pressure 20 on the key pressing this pawl forcibly against lock bail 254, and unless these parts are properly related, pawl 265 would tend to bind the bail 254 and prevent it from releasing the key when latch 280 releases bail 254. 25 If, however, the lower end of pawl 265 is provided with a slight camming angle, as shown in the drawings, pressure applied to the multiplier key will tend to force bail 254 toward its normal position, so that when latch 280 is 30 released pawl 265 will cam over the bail 254 and the multiplier key will be free to initiate the intended multiplier operation.

Should a multiplier key be held in depressed position by the operator, bail 250 will 35 return to its normal position at the proper time and the machine will be stopped in accordance with the value of the key. In such case slide 252 will be held in forward position by engagement of its projection 259 with the 40 front face of the key stem. Upon manual release of the key slide 252 will return to normal position.

The multiplier mechanism is so designed that during the depression of a multiplier key 45 the subtract key will be locked in raised position, and during the depression of the subtract key the multiplier keys will be locked in raised position. This is due in the first instance to the latching of bail 250 and lever 50 255 in the position shown in Fig. 15 upon the depression of a multiplier key, whereby the rise of roller 267 and the rocking of shaft 125 in a clockwise direction from the position shown in Fig. 26 will be prevented. On the 55 other hand, depression of the subtract key (Fig. 9) will act to raise roller 267 to a position above the cam edge 266 of lever 255 and in the path of movement of said lever, whereby bail 250, slide 252 and keys 261 will be 60 locked in the position shown in Fig. 14.

Should a transitional carry occur in multiplication, owing to accumulation upon numeral wheels 13, in excess of the capacity provided by the carry mechanism, the multiplier means are designed to permit revers-

ing clutch lever 111 to be moved to neutral position, since the bail now stands in an intermediate position determined by the stop wall of notch 263 of the key. Shaft 125 and setting lever 128, therefore, stand in a partially retracted position, wherein pin 130 is allowed sufficient movement in slot 129 to provide for said movement of lever 111 to neutral. Under such conditions, the loss of carry will, of course, give an incorrect registration 70 upon the numeral wheels, and it is desirable that the error be called to the attention of the operator. This is done by the stopping of the machine with the multiplier keys remaining locked, since the key locks are not released 75 until the successive revolutions of cam 276 have advanced slide 252 sufficiently to bring the tooth thereof out of registration with the key notch.

The loss of carry being noted, it is necessary to continue the interrupted rotations until the multiplier keys are released. The tripping of trigger 31 by the numeral wheels will leave pawl 136 set to trip said trigger again upon release of the multiplier key. Depression of the add key will serve to move shaft 125 from the position illustrated in Fig. 26 to that of Fig. 8, whereupon the clutch will be re-engaged in additive position. Finger pressure being immediately removed from the add key, pawl 136 will be held depressed until the release of the multiplier key, whereupon the operation will be terminated. It is to be noted that upon interruption of the operation, the subtract key 100 will remain ineffective, and that any key capable of re-engaging the clutch will act under these conditions to complete the multiplier operation.

Rotation of crank handle 3, attached to 105 driving gear 76, would also serve to continue the multiplication and advance the slide. Upon the final cycle of predetermined operation, the multiplier keys will be released, this serving as a signal to the operator to bring 110 the parts to rest with the crank handle in full-cycle position. The loss of carry having been noted, the operator may, if desired, correct the product reading by moving the carriage and registering the numeral 1 in the proper 115 place.

I claim:

1. In a calculating machine having numeral wheels, actuating means therefor, driving means for said actuating means including a motor, and a clutch between said driving means and said actuating means, a plurality of multiplier keys of differing numerical value, a control member movable upon depression of any multiplier key and held 120 thereby in position to effect the clutch and to determine additive registration upon said numeral wheels, a member progressively advanced in the operation of said actuating means and acting to release said control mem- 130

ber from the depressed multiplier key on the determination of a number of cycles of operation corresponding to the value of said depressed key, cooperating mechanism operable

- 5 to release the clutch and bring the actuating means to rest upon release of said control member, and a key depressible to effect the clutch and to determine subtractive registration upon said numeral wheels, said cooperating
- 10 means being operable upon manual release of said last named key to release the clutch and bring the actuating means to rest, and said control member acting to lock the subtract key in raised position while a multiplier key
- 15 is depressed and to lock the multiplier keys in raised position while the subtractive key is depressed.

2. In combination with a calculating machine having numeral wheels, actuating means therefor, stopping means for said actuating means, and means controlled by a given registering movement of the numeral wheels for operating said stopping means to terminate the registration, a plurality of multiplier keys of differing numerical value, and means operated upon depression of a multiplier key to effect registration upon said numeral wheels, and normally operating to maintain registering action for a number of cycles corresponding to the value of the depressed key, and adapted upon said given movement of the numeral wheels to terminate the registration irrespective of said value.

3. The combination with a calculating machine having numeral wheels, actuating means therefor, stopping means for said actuating means, and means controlled by the numeral wheels for operating said stopping means to terminate a registration, a plurality of multiplier keys of differing numerical value, and means operated upon depression of a multiplier key to effect registration upon said numeral wheels, normally operating to maintain a registering action for a number of cycles corresponding to the value of the depressed key, and adapted, following interruption by said stopping means, under the control of the numeral wheels, to determine the completion of the interrupted registering action.

4. In combination with a calculating machine having numeral wheels, actuating means therefor, stopping means for said actuating means, and means controlled by a given registering movement of the numeral wheels for operating said stopping means to terminate a registration, a plurality of multiplier keys of differing numerical value, and means operated upon depression of a multiplier key to effect registration upon said numeral wheels, and adapted upon said given movement of the numeral wheels to terminate the registration irrespective of said value, and means operable invariably to lock

a multiplier key in depressed position until a number of cycles of registering operation have been effected corresponding to the value of said key.

5. In a calculating machine having numeral wheels, differentially settable multiplicand mechanism, a plurality of multiplier keys of differing numerical value, and means including a periodically advanced member for registering upon said numeral wheels products of values set in said multiplicand mechanism in accordance with the value of a depressed key; means operable upon depression of said key to lock the other multiplier keys in raised position, and means for automatically releasing the keys from the locking means after said member has completed its periodical advance.

6. In a calculating machine having numeral wheels, differentially settable multiplicand mechanism, a plurality of multiplier keys of differing numerical value, and means for registering upon said numeral wheels products of values set in said multiplicand mechanism in accordance with the value of a depressed key, including cyclically operated actuators; means operable upon depression of said key to lock the other multiplier keys in raised position, and means operated by the actuators to release the keys from the locking means.

7. In a calculating machine having numeral wheels, differentially settable multiplicand mechanism, a plurality of multiplier keys of differing numerical value, and means for registering upon said numeral wheels products of values set in said multiplicand mechanism in accordance with the value of a depressed key, including cyclically operated actuators; means operable upon depression of said key to lock the other multiplier keys in raised position, and means for releasing the keys from the locking means upon an extra-cyclic movement of said actuators.

8. In a calculating machine having numeral wheels, differentially settable multiplicand mechanism, a plurality of multiplier keys of differing numerical value, and means for registering upon said numeral wheels products of values set in said multiplicand mechanism in accordance with the value of a depressed key; means operable upon depression of said key to lock the other multiplier keys in raised position, means for latching the locking means in active position, and means for automatically releasing the latch after the completion of said product registration.

9. In a calculating machine having numeral wheels, differentially settable multiplicand mechanism, a plurality of multiplier keys of differing numerical value, and means for registering upon said numeral wheels products of values set in said multiplicand mechanism in accordance with the value of

- a depressed key; means operable upon depression of said key to lock the other multiplier keys in raised position, said locking means being adapted to release under finger pressure
5. upon the keys; means for latching the locking means in active position; and means for automatically releasing the latch after the completion of said product registration.
10. In a calculating machine having numeral wheels, differentially settable multiplicand mechanism, a plurality of multiplier keys of differing numerical value, and means for registering upon said numeral wheels products of values set in said multiplicand
15. mechanism in accordance with the value of a depressed key; means operable upon depression of said key to lock the other multiplier keys in raised position and adapted to lock the operated key in raised position upon release thereof, and means for moving the locking means automatically to inactive position.
20. 11. In a calculating machine having numeral wheels, differentially settable multiplicand mechanism, a plurality of multiplier keys of differing numerical value, and means for registering upon said numeral wheels products of values set in said multiplicand mechanism in accordance with the value of a depressed key; means operable upon depression of said key to lock the other multiplier keys in raised position and adapted to lock said key in depressed position and to release the key upon determination of said product registration; means operable upon depression of said key to lock the other multiplier keys in raised position, and means for
25. releasing the keys automatically from the locking means after the completion of said product registration.
20. 12. In a calculating machine having numeral wheels, registering means including a motor and control devices selectively operable by a single manual stroke to effect positive or negative registration upon said numeral wheels; multiplier mechanism including control keys manually operable to effect positive registration upon said numeral wheels, and means adapted to prevent negative registering action of said control devices at any time while a multiplier key is in active position.
30. 13. In combination with a calculating machine having numeral wheels, actuating means therefor, driving means for said actuating means including a motor, a clutch between said driving means and said actuating means, stopping means for said actuating means including unclutching devices, and means controlled by the numeral wheels for operating said stopping means; a plurality of multiplier keys of differing numerical value, controlling means operated upon depression of a multiplier key to effect the clutch, normally operating to maintain a registering action for a number of cycles corresponding to the value of the depressed key, and adapted, following interruption by said stopping means, under the control of the numeral wheels, to hold the reverse operation key locked and to complete the interrupted operation upon depression of the forward direction operation key.
35. 14. In combination with a calculating machine having numeral wheels, actuating means therefor, driving means for said actuating means including a motor, a clutch between said driving means and said actuating means, stopping means for said actuating means to engage said clutch following interruption by said stopping means under the control of the numeral wheels to complete the interrupted registering action automatically.
40. 15. In a calculating machine having reversible numeral wheels, reversible actuating means therefor, driving means for said actuating means including a motor, a clutch between said driving means and said actuating means, operation keys, devices operable thereby to engage said clutch and to determine forward or reverse operation stopping means for said actuating means including unclutching devices, and means controlled by the numeral wheels for operating said stopping means; a plurality of multiplier keys of differing numerical value, controlling means operated upon depression of a multiplier key to effect the clutch, normally operating to maintain a registering action for a number of cycles corresponding to the value of the depressed key, and adapted, following interruption by said stopping means, under the control of the numeral wheels, to hold the reverse operation key locked and to complete the interrupted operation upon depression of the forward direction operation key.
45. 16. In a calculating machine having numeral wheels, actuating means therefor, driving means for said actuating means including a motor, a clutch between said driving means and said actuating means, and stopping means for said actuating means including unclutching devices; a plurality of multiplier keys of differing numerical value, controlling means including a member movable upon depression of a multiplier key from neutral through active to set position, and co-operating mechanism adapted in the active position of said member to engage the clutch and to place said stopping means under restraint and in the set position of said member to free the clutch from control and to maintain the stopping means under restraint, and mechanism operable to release said member from set position

and thereby effect the stop at the conclusion of a number of cycles of operation corresponding to the value of said key.

17. In a calculating machine having numerical wheels, actuating means therefor, driving means for said actuating means including a motor, a clutch between said driving means and said actuating means, and stopping means for said actuating means including unclutching devices; a plurality of multiplier keys of differing numerical value, and provided each with a cam face and a stop wall located in a plane of movement intersecting an intermediate point of the cam face, controlling means

including a bail and a member held thereby in contact with said key, and co-operating mechanism adapted through movement of said member by the cam face of the key to engage the clutch and during contact of said member with the stop wall of the key to hold said stopping means under restraint, and mechanism operable to release said member from the key and thereby effect the stop at the conclusion of a number of cycles of operation corresponding to the value of said key. 15 20 25

In testimony whereof I affix my signature.

GEORGE C. CHASE.
